US00D813784S

(12) **United States Design Patent** (10) **Patent No.:** **US D813,784 S**
Larsson et al. (45) **Date of Patent:** **** Mar. 27, 2018**

(54) **CARRIER**

- (71) Applicant: **Thule Sweden AB**, Hillerstorp (SE)
(72) Inventors: **Johan Larsson**, Huskvarna (SE); **Jan Adler**, Skillingaryd (SE)
(73) Assignee: **Thule Sweden AB**, Hillerstorp (SE)
(**) Term: **15 Years**
(21) Appl. No.: **29/570,676**
(22) Filed: **Jul. 11, 2016**
(51) LOC (11) Cl. **12-11**
(52) U.S. Cl. **USPC D12/407; D12/400; D12/406**
(58) **Field of Classification Search**
USPC D3/304-306; D6/552, 716.3; D8/356;
D12/111, 115, 120, 159, 161, 169, 400,
D12/402, 406-408, 412, 414, 414.1, 420
CPC Y10S 224/924; B60R 9/048; B60R 9/06;
B60R 9/10
See application file for complete search history.

(57) **CLAIM**

The ornamental design for a carrier, as shown and described.

DESCRIPTION

FIG. 1 is a top front perspective view of a carrier showing the claimed design;

FIG. 2 is a bottom front perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a top front perspective view of a carrier showing the claimed design;

FIG. 10 is a bottom front perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof; and,

FIG. 16 is a bottom view thereof.

The broken lines in the figures show portions of the carrier that form no part of the claimed design.

1 Claim, 16 Drawing Sheets
